APPARATUS FOR FACILITATING SPLITTING OF CORD WOOD AND THE LIKE

Paul Field, Journey's End Road, New Canaan, Conn.

Filed Oct. 26, 1962, Ser. No. 233,384

3 Claims. (Cl. 269—86)

This invention relates to a device for facilitating splitting of cord wood and the like, for use, for example, in fire places and stoves. No such device is commercially available. While standards for Christmas trees have been proposed and are commercially available, they are not suitable for holding lengths of cord wood while it is being split. One reason for this is because a holder for cord wood must absorb the shock of the blows of an axe, or a sledge hammer or maul transmitted through a wedge. Another reason is the fact that the ground surface on which the length of cord wood is upended is not level and hard as in the case of a floor.

An object of the invention is to provide such a device which will be simple, effective and durable.

Another object of the device is to provide a device for holding a length of cord wood in upright position while it is being split which will be quickly adaptable to lengths of wood of different diameter and will provide effective support lengths of wood of different diameter.

The invention will best be understood if the following description is read in connection with the drawings in which:

FIG. 1 is a perspective view of a device embodying the invention;

FIG. 2 is a view showing in perspective three different forms of arms adapted for use in an embodiment of the invention; and

FIG. 3 is a plan view showing the device with its arms in at rest position.

As illustrated herein, the device comprises a base defined by three strips of iron 10, 12 and 14, of equal length, each having end portions 10a, 10b, 12a, 12b; and 14a, 14b bent outwardly at an angle of substantially 45°. The three strips are arranged to form a triangular frame but with their end portions spaced apart and disposed in parallel relation. Rotatably supported by and between the pairs of end portions respectively are the pivot rods 16, 18, and 20. The members 10, 12, and 14 are rigidly interconnected by brackets 22, 24, and 26 which bridge the spaces between the adjacent ends of said members just inwardly of the pairs of opposed parallel end portions of said members, 10a, 14a, 10b, 12a, and 12b, 14b respectively. Each bracket has end portions bent to lie flat against the inside surfaces of the triangle forming members which they interconnect, and the said bent portions may be welded or bolted or otherwise secured to the members in any satisfactory manner.

Mounted for rotation on the pivot rods 16, 18, and 20 are the arms 28, 30 and 32. Means are provided for causing the side edges of the arms to frictionally engage the bent over end portions of the frame members between which the pivot rods are respectively mounted. For this purpose lock washers 33 may be employed positioned around each pivot rod between the edges of the arm pivoted on said pivot rod and the inner surfaces of the opposed end portions of the frame members between which the pivot rod is supported. This construction enables the arms to stand in a raised position.

The arm members shown in the drawings are long enough to reach and engage between their elevated outer ends a length of wood of small diameter or a length of wood of substantially larger diameter, the arms being elevated at different angle depending upon the diameter of the length to be engaged. The arcs described by the free

2

ends of the arms enables them to engage lengths of wood placed between them throughout a wide range of inclinations of the arms, and the weight of the arms and the fractional grip between them and their pivot rods respectively is such that the engagement of the arms with the length of wood is positive. Once the arms have been placed with their inner ends against the length of wood, their contact with the length of wood is not disturbed by the blows of an axe or sledge hammer or maul upon the upper end of the length.

Preferably the arms are made long enough so that in their at rest positions in the plane of the frame their free ends will overlap one another. In FIG. 1 the device is shown employing arms of the kind illustrated by FIG. 2B, with the tubular member 34 at the pivot end and with the free end cut straight across. The pivot rods are, of course, inserted endwise through the tubular ends 34 of the arms and the parallel end portions of the frame members by which they are supported.

In FIG. 2A a modified form of arm is shown, the inner end being bent over to provide a substantially tubular portion 36 to receive a pivot rod, and the outer end portion 38 being curved in a direction away from a length of wood engaged by the outer end of the arm.

In FIG. 2C a tubular member similar to 34 in FIG. 2B is shown, and at the outer end of the arm a member 40 is shown which is curved concavely. The specific member is a segment of the arc of a circle and is adapted to provide extended contact around a portion of the perimeter of a length of wood.

The apparatus illustrated above functions effectively to hold in upright position lengths of cord wood varying in diameter through a range of diameters. By modifying the size of the apparatus including the arms 10, 12 and 14 the range of diameters of lengths of wood which can be effectively held in position by the device may also be modified.

The stiff action of the arms is of practical advantage since the arms may be first elevated, and do not have to be held up, while a length of wood to be split is positioned within the frame. The arms are then moved down until their outer ends abut against the periphery of the length of wood.

There has thus been provided a structure in which the above mentioned objects are accomplished in a thoroughly practical manner.

What is claimed is:

1. Apparatus for holding upright a length of cord wood and the like for splitting which comprises, a base, a number of arms pivoted to the base and extending inwardly of the base, and mounted for movement from an at rest position in which each arm is disposed substantially in the plane of the base to a position in which each arm is inclined upwardly to engage the sides of a length of cord

wood and the like placed on end within the area defined by the base, at least one of the arms being curved concavely at its outer end in the plane of the arm to partly encircle a length of cord wood or the like when moved into contact with it.

2. Apparatus for holding upright a length of cord wood and the like for splitting which comprises, three frame members disposed in the form of a triangle, the ends of the members being bent outwardly at an angle of substantially 45°, so that each apex of the triangle is defined by a pair of bent over ends spaced apart and substantially parallel, means interconnecting each member to each of the others adjacent to, and inwardly of, the parallel bent over end portions, pivot rods mounted between opposed, substantially parallel, bent over end portions of the frame members, and arms pivoted on said pivot rods and extending in the direction of the center of the triangular frame.

70

3. The device claimed in claim 2 in which means are provided between the sides of the arms where they are mounted on the pivot rods and the bent over ends of the frame members between which the pivot rods are respectively mounted, giving stiffness to the rotary movement of the arms on their pivots respectively and enabling each arm to stand in a raised position thus facilitating the

4
placing of the length of cord wood and the like on end within the frame.
